J. W. GRAY

CLOSURE MEANS FOR FILLING OPENINGS

Filed Nov. 18, 1925

FIG-1

FIG-2

FIG-3

J. W. GRAY INVENTOR

BY
Merrill M. Blackburn
ATTORNEY

UNITED STATES PATENT OFFICE.

JAMES W. GRAY, OF KEITHSBURG, ILLINOIS.

CLOSURE MEANS FOR FILLING OPENINGS.

Application filed November 18, 1925. Serial No. 69,832.

My invention relates more especially to automatically closing covers for the filling openings of gasoline tanks but is not necessarily limited to such use.

5 Among the objects of this invention are to provide a cap for a filling opening which will automatically close said opening when released; to provide a closure of the type indicated which will prevent the escape of 10 gasoline from a tank in which the same is kept; to provide vent means for such a tank which will permit air to pass from the outside into the interior of the tank and yet will prevent any water from passing through 15 the venting opening into the tank; to provide an improved means for closing a cap of the kind referred to; and such further objects, advantages and capabilities as will hereafter more fully appear and as are inherent in the construction disclosed.

20 My invention further resides in the combination, construction and arrangement of parts illustrated in the accompanying drawing and, while I have shown therein a preferred embodiment of my invention, I desire the same to be understood as illustrative only and not as limiting said invention.

In the drawing annexed hereto and forming a part hereof, Fig. 1 is an elevation showing a portion of a gasoline tank in dotted lines and the position of my invention with relation thereto; Fig. 2 is an enlarged vertical sectional elevation of my new closure means in closed position; and 35 Fig. 3 is a lateral elevation corresponding to Fig. 2 but with the closure means in open position.

Referring more in detail to the annexed drawing, numeral 1 designates a tank of 40 any desired size, shape or construction, having a filling opening in one face thereof, preferably the upper face, around which filling opening there customarily rises a flange which is screw-threaded externally. 45 It will of course be understood that if the flange is screw-threaded internally the construction of the lower portion of my device will have to be correspondingly modified in order to be adapted thereto. Secured to 50 this upstanding flange of the tank is a ring 2 having its lower end 3 screw-threaded for attachment to the flange of the tank. It will of course be understood that if the tank flange is designed for application of a construction using a bayonet slot connection or other equivalent device, this portion of my

device will have to be modified accordingly to cooperate therewith.

The upper portion of the ring 2 is preferably inset with relation to the portion 3, 50 forming a shoulder 4 against which is secured a ring 5 which forms an internally projecting flange adjacent the lower portion of the ring 2. A gasket 6 rests against the underside of the flange 5 and assists in 55 sealing the connection between the tank and the ring 2 so that gasoline can not escape through the threads or equivalent connecting means joining this device to the tank. The ring 2 is undercut, reamed, or spun outwardly at 7 so that a groove is formed in which the gasket 8 may rest and be prevented from accidental removal through the filling opening. This gasket is pressed 60 tightly to the flange 5 by the cap to be 70 presently described.

Extending laterally from the ring 2 is a projection 9 which is preferably hollow for the reception of the end 10 of the lever 11 which is pivoted at 12. A rivet, bolt, or 80 other suitable rigid securing means 13 extends through the hollow interior of the projection 9 and to this is secured one end of the resilient means 14 shown as a coil spring. From its pivot 12 the lever 11 rises and then is 85 bent laterally and downwardly in a goose neck 15, being bent laterally again at 16 to serve as holding means for a cap 17. This cap has its edge turned downwardly as shown at 18 to surround the upper edge of 90 the ring 2 but fits around the same loosely enough so that there is no difficulty in opening or closing this cap. The extreme end of the lever 11 may be used as a means for 95 lifting this cap against the tension of the spring 14. The lever and cap are perforated for the reception of securing means 19, shown in the present instance as a bolt having its head external to the cap, though it may, if desired, be reversed and the screw-threaded end of the bolt may engage a correspondingly threaded opening in the lever 11. Also, it is possible to use a rivet in this 100 location if desired but the present construction is deemed preferable.

A protuberance in the form of a cup 20 projects inwardly from the inner face of the cap 17 and at its lower end presses against the gasket 8 to hold the same in tight engagement with the flange 5 whereby gasoline is substantially prevented from escaping 105 between the flange and the protuberance.

Furthermore, this gasket is so far below the upper edge of the ring 2 that not enough gasoline can escape between the flange and the protuberance to make it possible for the gasoline to splash over the top of the ring. This means is considered a very effective means for doing away with the customary loss of gasoline due to the splash thereof in the tank. Vent openings 21 and 22 permit air to pass from the exterior of the tank to the interior thereof as needed to permit the gasoline to be fed into the carburetor of an engine. It will be noticed that these openings are so far apart that it will be impossible for gasoline to collect in the cup to a sufficient amount so that it will escape through the opening 22 and over the top of the ring 2. There is enough clearance between the cap and the top edge of the ring 2 so that all the needed air may pass in between the cap and ring but the downwardly extending flange 18 will prevent rain and road splashing from entering into the ring and from there into the tank. This protection of the vent opening is considered substantially equally important with the location of the sealing joint between the parts 20, 8 and 5 remote from the top of the ring 2.

30 It will be obvious from the foregoing that this construction is adapted for the accomplishment of the various objects set forth above and that various changes in the construction herein disclosed may be made 35 without departing from the spirit of my invention.

Having now described my invention, I claim:

1. In closure means for filling openings 40 having an upstanding flange, an internally threaded ring adapted to be secured to the flange, a flange projecting inwardly on the inside of the ring at a point remote from its upper edge, a gasket resting against said 45 second mentioned flange, a cap pivoted externally of the ring and provided on its inner face with an inwardly projecting closure member for the gasket, said member adapted to seat tightly against the gasket to substantially prevent passage of fluid outwardly between the gasket and its closure member.

2. In closure means for filling openings 55 having an upstanding flange, an internally threaded ring adapted to be secured to the flange, a flange projecting inwardly on the inside of the ring at a point remote from its upper edge, a gasket resting against said second mentioned flange, a cap pivoted externally of the ring and provided on its inner 60 face with an inwardly projecting closure member for the gasket, said member adapted to seat tightly against the gasket to substantially prevent passage of fluid outwardly between the gasket and its closure member, said gasket closure member being pro-

vided with air vent openings to permit venting of air through same.

3. In a closure means for filling openings, a ring having an inwardly extending flange adjacent its lower portion, said ring having 70 an internal depression extending around the inner face thereof adjacent the flange, a gasket within the ring and seated in said depression, and a resiliently actuated cap pivoted on said ring and provided on its inner 75 face with a protuberance adapted to rest against the gasket and substantially prevent passage of fluid through the opening in the gasket and outwardly beyond the same.

4. In a closure means for filling openings, a ring having an inwardly extending flange adjacent its lower portion, said ring having 80 an internal depression extending around the inner face thereof adjacent the flange, a gasket within the ring and seated in said depression, and a resiliently actuated cap pivoted on said ring and provided on its inner 85 face with a protuberance adapted to rest against the gasket and substantially prevent passage of fluid through the opening in the gasket and outwardly beyond the same, said protuberance having a passageway there-through, one end of which opens upon the inner face of the protuberance and the other end of which opens adjacent the under face 90 of the cap.

5. In a closure means for filling openings, a ring having an inwardly extending flange adjacent its lower portion, said ring having 100 an internal depression extending around the inner face thereof adjacent the flange, a gasket within the ring and seated in said depression, and a resiliently actuated cap pivoted on said ring and provided on its inner 105 face with a protuberance adapted to rest against the gasket and substantially prevent passage of fluid through the opening in the gasket and outwardly beyond the same, said protuberance having a passageway there-through, one end of which opens upon the inner face of the protuberance and the other end of which opens adjacent the underface 110 of the cap, said cap having a depending flange surrounding and spaced from the protuberance.

6. In closure means for filling openings of gasoline tanks and similar structures, a ring adapted to be secured to the tank, an inwardly projecting flange in the ring remotely positioned from that end of the ring which is directed away from the tank, a cap pivoted externally of the ring projecting inwardly toward, and adapted to press against said flange, and a gasket between the flange and cap whereby to substantially prevent passage of fluid outwardly between the flange and cap.

7. In closure means for filling openings of gasoline tanks and similar structures, a ring adapted to be secured to the tank, an in-

wardly projecting flange in the ring remo- flange and cap, said cap having an opening
tely positioned from that end of the ring from the inner face thereof to its circumfer- 10
which is directed away from the tank, a cap ential face in the vicinity of the outer end
pivoted externally of the ring projecting in- of the ring.
wardly toward, and adapted to press against In witness whereof, I hereunto subscribe
said flange, and a gasket between the flange my name to this specification.
and cap whereby to substantially prevent
passage of fluid outwardly between the
